UNITED STATES PATENT OFFICE.

LEO GUDEMAN, OF NEW YORK, N. Y.

LAMP VAPORIZER.

1,403,548.

Specification of Letters Patent. Patented Jan. 17, 1922.

Application filed September 10, 1920. Serial No. 409,499.

To all whom it may concern:

Be it known that I, LEO GUDEMAN, a citizen of the United States, residing at New York city, in the county of New York and State of New York, have invented certain new and useful Improvements in Lamp Vaporizers, of which the following is a specification.

My invention relates to improvements in vaporizing attachments for electrically lighted incandescent bulbs and more particularly to devices of this character wherein a receptacle is supported by embracing a portion of the surface of said bulb.

The object of the present invention is to provide a receptacle for the reception of fluid disinfectant, deodorizer, perfume, or the like, for the purpose of vaporizing the latter by means of the heat radiating from an electrically lighted incandescent bulb, the latter providing a support for the receptacle.

A further object of this invention is the provision of a receptacle adapted to embrace a portion of the surface of an electric light bulb without substantially diminishing the light emanating from the bulb.

Devices of this general character have been employed in connection with oil lamps, gas burners, and even with electric-bulbs to vaporize a fluid for the purpose of distributing moisture from a receptacle, but the latter has either been supported a distance above the heating medium or, as in the case of the electric heating medium, the receptacle entirely surrounds the bulb thereby limiting the efficiency of the bulb to a heating medium and practically destroying its use as a light. A device in accordance with my invention does not substantially diminish the illuminating properties of the bulb. This feature of the invention is particularly important where the device is to be used in a theatre or assembly for disinfecting purposes, such as required by law in some localities, as the device may be attached to the bulbs without obstructing the light-rays issuing therefrom. A shade or other ornamental means may also be used in connection with the receptacle; in fact the latter may be entirely screened from view and still retain the function of dispensing vaporized fumes therefrom. It will be noted from the following description that the device may be made in different forms so as to be applicable to bulbs held in a vertical position as well as in an inverted position.

The material used in the manufacture of a device of this character may be either metal or glass, or any other suitable material capable of retaining fluid and at the same time able to withstand sufficient heat to vaporize the fluid therein.

The invention consists in the structural features hereinafter fully described with reference to the accompanying drawing, 65 wherein

Fig. 1 is a perspective view of the improved vaporizer.

Fig. 2 is a substantially vertical sectional view through the vaporizer when supported 70 by a bulb in vertical position.

Fig. 3 is a sectional view of a slightly modified form of the vaporizer supported by a vertically disposed bulb.

Fig. 4 is a sectional view of still another 75 form of vaporizer supported by an inverted bulb.

Fig. 5 is a sectional view of a form of the vaporizer adapted for use in connection with a nitrogen lamp or bulb.

Referring to the drawing, Figs. 1 and 2; 10 denotes a receptacle for the reception of fluid shown at 11. The receptacle 10 consists of an inner member or wall 12 which is preferably hemispherical in form and 85 provided at its apex with a teat 13. The wall 12 is designed to conform to the globular portion of an electrically lighted incandescent bulb 14. The lowermost portion of the member 12 has as great a diameter 90 as the greatest diameter of the dome and its lower edge is turned outwardly at substantially right angles to form a concentric flange 15. Secured to the flange 15 adjacent the bend of the latter is the lowermost edge 95 of a shell 16, having an opening 17 at its upper end through which the fluid may be poured and the vaporized fumes escape.

From the foregoing description it will be observed that the receptacle depends entirely upon the bulb 14 for support and also for heat, the latter acting to vaporize the fluid 11 in the receptacle. In order that the inner surface of the member 12 may closely embrace the surface of the bulb 14, a coating 105 of heat conducting material 18 is provided, the latter also preventing the receptacle 10 from becoming unseated.

In Fig. 3, the receptacle 10^a is formed up out of one piece of material the metal being 110 spun back upon itself and flared in opposite directions at the open end. This form pro-

vides a channel 19, for the reception of the fluid 11, and the convergence of the upper and inner portion of the wall provides a surface adapted to conform in shape to the 5 globular portion of the bulb 14. This form of receptacle is particularly adaptable to lamps wherein it is desired to allow the upper end of the bulb to be exposed.

In Figs. 4 and 5, the construction of the 10 receptacle is of such design that it may be supported upon an inverted bulb, the inner wall 20 of the receptacle 10^b of Figure 4 conforming in shape to the tapering side wall of the bulb 14^a and the wall 20^a of the 15 receptacle 10^c of Fig. 5 conforming in shape to the body of the bulb 14^b, thereby permitting the receptacle to snugly embrace the surface of the bulb without interfering with its lighting properties.

20 In the use of the device either as a disinfectant dispenser, deodorizer, or for evaporating any medical preparation by means of heat for discharging vaporized fumes in a room, the receptacle 10 is placed upon an

electrically lighted incandescent bulb or lamp 18 in the manner described. A sufficient quantity of liquid is placed in the receptacle 10 and the electricity turned on, whereupon the glass bulb 14 will be sufficiently heated to heat the inner wall or dome 12 and cause the fluid 11 to vaporize. The fumes from the vaporizing fluid will issue through the opening 17 in the outer member 16 to the surrounding atmosphere.

The device may be used with a table lamp or hanging lamp and when so used I may provide concentrated perfume tablets, soluble in water, placed in the receptacle 10.

I claim:—

A vaporizing device comprising an outer wall and spaced therefrom an inner wall conforming substantially in shape to and adapted to directly engage an electric light bulb whereby said device may be supported in vaporizing position solely by said bulb.

In testimony whereof I have affixed my signature.

LEO GUDEMAN.
